US0D1044835S

(12) **United States Design Patent** (10) Patent No.: **US D1,044,835 S**
(45) Date of Patent: ** Oct. 1, 2024

(54) **DISPLAY SCREEN OR PORTION THEREOF WITH GRAPHICAL USER INTERFACE**

(71) Applicant: **Apple Inc.**, Cupertino, CA (US)

(72) Inventors: **Christian Xavier Dalonzo**, San Francisco, CA (US); **Alan C. Dye**, San Francisco, CA (US); **Eileen Y. Lee**, San Francisco, CA (US); **William McMillan Tyler**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/845,643**

(22) Filed: **Jul. 8, 2022**

Related U.S. Application Data

(63) Continuation of application No. 29/738,923, filed on Jun. 21, 2020, now Pat. No. Des. 957,412.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
